(57) **CLAIM**

I claim the ornamental design for a siding panel, as shown and described.

DESCRIPTION

FIG. 1 is a perspective view of the article;

FIG. 2 is top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The siding panel is broken in the center to indicate indefinite length and width thereof.
